UNITED STATES PATENT OFFICE

HENRY C. MITCHELL, OF NATURITA, COLORADO, ASSIGNOR OF ONE-HALF TO
PAUL STARK SEELEY

ORE CONCENTRATOR

Application filed October 8, 1931. Serial No. 567,566.

My invention relates to that class of devices which are designed to separate fine and light free gold from placer gravel.

My invention has for its object to construct a device which will be more efficient in its operation by an increased recovery of the fines than is possible with the present forms of apparatus employed for this purpose.

My invention has for a further object to provide a device which will operate equally well with mill slimes.

A further object is to provide a device which will be most economical and efficient for use on dredges employed for the recovery of gold in rivers and along their courses.

My means of accomplishing the foregoing objects may be more readily understood by having reference to the accompanying drawings, in which—

20 Fig. 1 is a plan view of my improvement;

Fig. 2 is a section taken on the line 2—2 of Fig. 1 in the direction indicated by the arrows;

25 Fig. 3 is a section taken on the line 3—3 of Fig. 1, in the direction indicated by the arrows; and

Fig. 4 is an enlarged fragmentary view of 30 Fig. 4 is an enlarged fragmentary view of a riffle. Similar reference numerals refer to similar parts throughout the entire description.

As shown in the drawings, my device consists of a riffle box 1, mounted above the riffle box is a grizzly 2 which preferably consists of a plate of iron provided with a plurality of perforations 3. These perforations should be preferably $\frac{1}{8}$ " to $\frac{1}{2}$ of an inch in diameter, depending upon the fineness of the gold and the character of the gravel or the nature of the mill slimes which are to be handled.

40 As shown, the grizzly 2 is supported upon shoulders 4 and 5, which should be approximately 1 inch above the riffle board 6 which forms the bottom of the riffle box 1. The riffle box 6 is provided with a plurality of 45 riffles 7, each of which has a continuous discharge. The first riffle starts 2 inches from the lead and on either side depending on whether it is designed to discharge to the right or left for a single riffle board may be 50 made to discharge either to the right or to

the left or the device may be made up with duplicate riffle boxes, one of which discharges to the right and the other to the left. It will be apparent to persons skilled in the art that the riffle boards 6 may be of any width desired limited only by the amount of water available for the sluice lead. The riffles 7 angle across the riffle board 6 at approximately an angle of 45°. They are undercut, as clearly shown in Fig. 4 of the drawings, and are preferably constructed with a depth of $\frac{1}{4}$ " at the initial point expanding to $1\frac{1}{4}$ " at its discharge point 8. I desire it to be understood that I do not wish to be limited to the exact shape of the riffles or the angle of 65 their inclination as any form may be used which will handle the material as needed. In practice I have found it desirable to provide for an inclination of the riffle board 6 of substantially 1 inch to 1 foot. The riffle 70 board may be constructed of any suitable material such as wood, metal, rubber products or any combination thereof which may be desirable. At the discharge end 8, of each riffle 7, I provide a round opening 9, which is directly in line with the bottom of 75 the riffle 7. The riffles constantly discharge the gold concentrates through these openings. Over these openings 9, I mount hoods 10, which are shaped as clearly seen in the 80 drawings with a reverse portion 11' which operates to reverse the direction of the flow and to throw the stream back towards the point of its discharge. The hood 10 terminates at a point 11 which is located close to 85 the bottom 12 of the launder 13 and spreads the flow evenly in a lamina across the entire width of the launder 13. In practice I have found it desirable to make these launders substantially six feet long, 15 inches wide and 90 two inches deep.

I have found in practice that a greatly increased recovery can be had by covering the floor 12 of the launders 13 with a fabric 14 which has a nap or weave into which the fine gold will settle such as carpet, burlap or similar material. The fabric is detachably secured in place by bolts 15 which are provided with wing nuts 16 for convenient removal.

95 The riffle box should be maintained ex- 100

actly level on its cross dimension but is given the longitudinal inclination heretofore mentioned. Obviously this may be varied to suit the character of the work such as the 5 quantity of water and the nature of the material handled.

The operation of the device is as follows:

The material is discharged onto the grizzly 2, the water flowing underneath will draw 10 the finer part thereof, which contains the values, through the perforations by hydraulic suction, while the coarser material, due to the 15 inclination, will pass to the tailing dump. It is well known that the fine gold will remain 20 in suspension in the presence of the gravel where the grade is greater than 1 inch to the foot more or less depending on the nature of the gangue. The fine values drop into the riffles, where the light finer precious metal values 25 are panned out by the water stream and the heavier fines are worked down the riffles and discharged into the hood 10. Since the finer gold values are still in suspension it is necessary, in order to throw it down, to spread 30 the stream and material carried by it in a lamina across the fabric 14. The nap or weave will catch and hold the fine gold. It is well known that a flowing stream of water 35 has a rolling movement due to the fact that the friction against the stream bed causes the water adjacent thereto to move slower than the top. I avail myself of this law and make use of this rolling motion to throw down the fine gold into the nap or weave of the fabric 40 from which it may subsequently be recovered by washing or amalgamation.

Although I have described and illustrated certain details of construction, it is to be understood I have done so only for the purpose 45 of disclosing a preferred embodiment of my invention which I have found in actual practice to be highly efficient; but this disclosure is not to be deemed a limitation except as such limitations appear in the hereinafter contained claims.

Having described my invention what I regard as new and desire to secure by Letters Patent is:

1. The combination with a grizzly, of a 50 riffle box below said grizzly, there being a plurality of lateral discharge outlets from said riffle at the ends of the riffles in said riffle box, a launder adjacent each discharge, a hood for each outlet which directs the flow backwards 55 towards said outlet and spreads it in a lamina which extends the width of said launder and a lining of fibrous material on the bottom of said launders.

2. The combination with a grizzly, of a 60 riffle box below said grizzly, a plurality of undercut riffles in said box which extend in an angular direction across said box, said cuts expanding from $1\frac{1}{4}$ " in depth at the upper end to $1\frac{1}{4}$ " at the lower or discharge end, 65 there being a plurality of outlets in said riffle

box at the discharge end of said riffles, a launder adjacent each discharge hood for each outlet which directs the flow backwards towards said outlet and spreads it in a lamina which extends the width of said launder, the bottom 70 of said launder being lined with fibrous material.

3. The combination with a grizzly of a riffle box, there being side openings in said box, riffles on said box, a discharge hood at 75 the end of said riffles, launders into which said hood directs the said discharge, a lining of rough surfaced material in said launder.

4. The combination with a grizzly of a riffle box, below said grizzly, there being side 80 openings in said box, a plurality of riffles in said box, said riffles being undercut, angular and expanding, a launder below each of said side openings, a discharge hood at each side opening which directs the flow back upon itself and forms a lamina in said launder, and a lining of rough surfaced material on the 85 bottom of said launder.

5. The combination with a riffle box having 90 side openings therein, of a plurality of riffles in said box, said riffles being undercut and angular and expanding from $\frac{1}{4}$ " in depth to $1\frac{1}{4}$ " in depth at the discharge, a launder at each side opening, a discharge hood at each side opening which directs the flow back upon itself which forms a lamina the width of the launder and a lining of 95 rough surfaced material on the bottom of said launder.

6. The combination with a grizzly, of a 100 riffle box below said grizzly, a plurality of riffles in said box, said riffles being undercut, angular and expanding, launders at each side opening, said launders having the bottoms lined with rough surfaced material and a 105 hood to spread the flow in a lamina over said rough surfaced material.

7. The combination with a grizzly, of a 110 riffle box below said grizzly, a plurality of riffles in said box, there being an opening in said box at the lower end of each riffle, a discharge hood for each of said openings which directs the flow back upon itself, launders below said openings, said hood forming a lamina, the width of said launders and a 115 lining of rough surfaced material at the bottom of said launders.

8. The combination with a grizzly, of a 120 riffle box below said grizzly, there being side openings in said box, a plurality of undercut expanding riffles in said box, a launder at each of said openings, a discharge hood for each of said openings which directs the flow back upon itself and forms a lamina which 125 extends the width of said launder and a lining of rough surfaced material for the bottom of said launders.

9. The combination with a riffle box having 130 a plurality of riffles in said box, said riffles being undercut, angular and expanding

and leading to side openings of a launder at each side opening, said launders having the bottoms lined with rough surfaced material and means to spread the discharge from said 5 riffles in lamina over said rough surfaced material.

10. The combination with a riffle box, of a plurality of riffles in said box, there being an opening in said box at the lower end of each 10 riffle, a discharge hood for each of said openings which directs the flow back upon itself, launders below said openings, said hood forming a lamina, the width of said launders and a lining of rough surfaced material at 15 the bottom of said launders.

11. The combination with a riffle box, there being side openings in said box, a plurality of undercut, expanding riffles in said box of a launder at each of said 20 openings, a discharge hood for each of said openings, which directs the flow back upon itself and forms a lamina which extends the width of said launder and a lining of rough surfaced material for the bottom of said 25 launders.

12. The combination with a grizzly, with a riffle box, below said grizzly, there being side 30 openings in said box, a plurality of riffles in said box, said riffles being undercut and expanding, of a launder below each of said side openings, a discharge hood at each side opening which directs the flow back upon itself and forms a lamina in said launder, a lining 35 of rough surfaced material on the bottom of said said launder.

13. The combination with a grizzly, of a 40 riffle box below said grizzly, there being side openings in said box, a plurality of undercut riffles in said box, of a launder at each of said 45 openings, a discharge hood for each of said openings which directs the flow back upon itself and forms a lamina which extends the width of said launder and a lining of rough surfaced material for the bottom of said launders.

14. The combination with a grizzly with 50 a riffle box, below said grizzly, there being side openings in said box, a plurality of undercut riffles in said box, said riffles being undercut, angular and expanding, of a launder below each of said side openings, a discharge hood at each side opening which directs the flow back upon itself and forms a lamina in said launder, a lining of rough 55 surfaced material on the bottom of said launder, and means to detachably secure said material to the bottom of said launders.

HENRY C. MITCHELL.
